CLAIM

The ornamental design for headphones, as shown and described.

DESCRIPTION

FIG. 1 is a rear right side perspective view of headphones showing my new design;

FIG. 2 is a right side view thereof;

FIG. 3 is a left side view thereof;

FIG. 4 is a rear view shown separately for the purposes of illustration;

FIG. 5 is a side view thereof;

FIG. 6 is a front view thereof;

FIG. 7 is an inside view thereof;

FIG. 8 is a bottom view thereof;

FIG. 9 is a top view thereof;

FIG. 10 is a side view thereof;

FIG. 11 is a rear view thereof;

FIG. 12 is an inside view thereof;

FIG. 13 is a front view thereof;

FIG. 14 is a top view thereof; and,

FIG. 15 is a bottom view thereof.

The broken lines depict environment that forms no part of the claimed design.

1 Claim, 9 Drawing Sheets
